(57) **CLAIM**

The ornamental design for a mobile device stand, as shown and described.

DESCRIPTION

FIG. 1 is an elevated perspective view of a mobile device stand in an open position in a first orientation, showing my new design;

FIG. 2 is an elevated perspective view of the mobile device stand in an open position in a second orientation;

FIG. 3 is a left side view thereof;

FIG. 4 is a right side view thereof;

FIG. 5 is a top plan view thereof;

FIG. 6 is a back plan view thereof;

FIG. 7 is a top side view thereof;

FIG. 8 is a bottom side view thereof;

FIG. 9 is an elevated perspective view of the mobile device stand in a closed position in a first orientation;

FIG. 10 is an elevated perspective view of the mobile device stand in a closed position in a second orientation;

FIG. 11 is a left side view thereof;

FIG. 12 is a right side view thereof;

FIG. 13 is a top plan view thereof;

FIG. 14 is a back plan view thereof;

FIG. 15 is a top side view thereof; and,

FIG. 16 is a bottom side view thereof.

The broken lines shown in FIGS. 1, 2, 9, and 10 depict a mobile device that forms no part of the claimed design.
